CLAIM

The ornamental design for a pressure control module, as shown and described.

DESCRIPTION

FIG. 1 is a front view of a pressure control module showing our new design;

FIG. 2 is a perspective view of the module;

FIG. 3 is a side view of the module;

FIG. 4 is a top view of the module; and,

FIG. 5 is a bottom view of the module.

FIG. 1

FIG. 2

FIG. 3

FIG. 4

FIG. 5
